UNITED STATES PATENT OFFICE

137,745

DESIGN FOR A MEDALLION OR SIMILAR ARTICLE

Louis A. Koch, Upper Saddle River, N. J.

Application July 23, 1943, Serial No. 110,739

Term of patent 7 years

(Cl. D29—19)

To all whom it may concern:

Be it known that Louis A. Koch, a citizen of the United States, residing at Upper Saddle River, in the county of Bergen and State of New Jersey, has invented a new, original, and ornamental Design for Medallion or Similar Article, of which the following is a specification, reference being had to the accompanying drawing, forming part thereof,

The figure is a perspective view of a medallion showing my new design.

I claim:

The ornamental design for a medallion or similar article, as shown.

LOUIS A. KOCH,
